SPIRIT DUPLICATOR

Ralph B. Segerstrom, Denver, Colo.

Application April 5, 1954, Serial No. 29,871

Term of patent 14 years

(Cl. D64—11)

Fig. 1

Fig. 2

Fig. 4

To all whom it may concern:

Be it known that I, Ralph B. Segerstrom, a citizen of the United States of America, residing at Denver, in the county of Denver and State of Colorado, have invented a new, original, and ornamental Design for a Spirit Duplicator, of which the following is a specification, reference being had to the accompanying drawing, forming a part hereof.

In the drawing:

Fig. 1 is a plan view of a spirit duplicator, showing my new design;

Fig. 2 is a side elevation thereof;

Fig. 3 is a rear view thereof; and

Fig. 4 is a front view thereof.

I claim:

The ornamental design for a spirit duplicator, as shown.
